CATHODE SUPPORT

Charles V. Litton, Redwood City, Calif., assignor
to Federal Telephone and Radio Corporation,
New York, N. Y., a corporation of Delaware

Application November 1, 1945, Serial No. 626,132

8 Claims. (Cl. 250—27.5)

1

This invention relates to vacuum tubes and in particular to a supporting means for filamentary cathodes. More specifically the invention provides an improved mechanical structure of great rigidity for supporting a filament of the bifilar type. Although the supporting structure may in general be employed with vacuum tubes of all types, it is particularly useful with magnetrons of the plural cavity type and therefore the preferred embodiment of my invention will be illustrated and described in connection with a tube of this type.

In addition to the improved mechanical features of my cathode support structure, there are also many advantages of an electrical nature, especially when employed with very high frequency generators such as magnetrons. For example, my improved support provides for substantially complete shielding against stray electron emission from the filament which otherwise tends to cause the magnetron to oscillate at undesired frequencies or modes. Means are also provided whereby the cathode may be made to assume substantially a radio frequency ground potential during operation.

It is therefore one of the objects of my invention to provide an improved type filament support possessing great rigidity and freedom from vibration.

Another object of my invention is to provide a rigid filament support that is particularly adapted for use with magnetrons of the plural cavity resonator type.

A further object is to provide a filament support that prevents stray electron emission from effecting the operation of the vacuum tube with which it is associated.

A further object is to provide a support for a filament that assumes substantially a radio frequency ground potential when in operation.

Additional objects and features of my invention will be apparent from the following description and the appended claims.

As above noted my invention will be described as it is embodied in the construction of a plural cavity magnetron and as illustrated in the attached drawings of which:

Fig. 1 is a cross sectional view of a plural cavity magnetron, the section being taken through what is essentially the axis of symmetry of the cathode and supporting structure therefor.

Fig. 2 is an enlarged section of the filament and its supporting structure showing more clearly and in greater detail the features of its construction.

2

Referring first to Fig. 1, reference character 1 represents the body of the magnetron to which other parts are brazed or otherwise suitably fastened until a structure capable of being evacuated has been formed. On one side of the body is a cylindrical extension 2 while on the other side there is a similar but shorter cylindrical extension 3, both extensions being brazed to the body 1.

The extension or housing 2 encloses an assembly 4 for adjusting the frequency to which the magnetron may be tuned as will be hereinafter described. This adjusting mechanism does not constitute a part of my present invention and a detailed description will therefore not be given.

However in general, a platform 5 is brazed to a Sylphon bellows 6 which is in turn brazed to a bearing holder 7, the latter being brazed to housing 2 along the circumference 8. When the magnetron is evacuated, the external atmospheric pressure tends to extend the bellows and force the platform 5 inwardly. This tendency must be constrained and a method for accomplishing same will now be described. A rod 9 is also brazed to the platform 5 and extends through the bellows and the bearing holder. A hardened and ground sleeve 10 is held in position over the rod by the tongue nut 11 and the lock nut 12. The tongues 13 fit into slots in the sleeve 10. When the nuts are tightened this prevents any relative motion between the rod and the sleeve.

A bearing 14 is positioned over the sleeve 10 and is clamped against the bottom of the bearing holder 7 by the inner ball race 15. The thrust bearing ball retainer with balls 16 and the outer ball race 17 are held against the race 15 by the atmospheric pressure and the nut 18, the latter bearing against the race 17. Relative rotation between the nut 18 and the sleeve 10 determines the extent of the longitudinal motion of the platform 5. A control knob 19 is fastened to the nut 18 for turning the latter. A scale 20 is located on the outer diameter of the knob and is aligned adjacent a fixed scale 21 on the indicator ring 22, the latter being clamped to the extension 2 as shown. A measure of the longitudinal motion is thus obtained.

On the aforementioned cylindrical extension 3 is mounted the cathode support assembly of my invention. A support cup 23 is brazed to the extension 3 and to a tubular sealing member 24. This member and the other members which are part of the metal to glass seals for insulating the cathode supporting members one from another is preferably made of a metal having approximately the same thermal expansion as hard glass

up to about 465° centigrade such as commercial alloys of iron, nickel and cobalt or other suitable material. Sealed to the member 24 is an insulating portion 25 followed by a series of three metal cups 26, 27, and 28 separated by glass portions 29 and 30.

To the metal cups are attached the two supporting members 31 and 32 for the cathode 33. Both supporting members may be frustums of cones as shown or they may be other conoidal shaped bodies. The dimensions of the conical frustums at the apical ends (point 34) are such that, were the cones annular at this point, they would intersect to form a common circle. However, the frustums are so mutilated that each of them at the point 34 are arcuate or semi-annular. In other words, if a plane, perpendicular to the common axis of the frustums, were passed through the point 34, the section would show two semi-circular arcs about a common center. The frustums are cut away or mutilated from their apical ends toward their bases a distance sufficient to permit the central support 35 to pass freely therethrough, i. e., without making electrical contact with the frustums.

From the point 34 to the ends of the members 31 and 32 their shape is substantially semi-cylindrical. These semi-cylindrical portions are welded or otherwise fastened to semi-cylindrical members 36 and 37. To the other ends of these semi-cylindrical members is attached the bifilar filamentary cathode 33, one end of one filament being connected to one member and one end of the other filament being connected to the other member. The opposite ends of the filaments are attached to a member 38. This member may be grooved as shown to improve its heat radiating properties. It will be noticed that the cathode extends into a recessed portion of the member 38 for the purpose of shielding the active region of the magnetron from undesired electron emission from that portion of the cathode within the recess. Similarly, there is connected to one of the semi-cylindrical members 37 a cylindrical ring member 39. This last named member also serves to shield the active region of the magnetron from undesired emission from the filament. It is well known that the ends of a filament are usually cooler than the central portion thereof due to heat being conducted to the filament supports. By shielding the ends of the filament as described above, that portion of the filament between the ends of the shields emits electrons substantially uniformly.

Connected to the Kovar cup 28 is a central support 35. From the end of the support nearer the cathode, a smaller rod 40 extends through the semi-cylindrical members, 36 and 37, the bifilar windings of the cathode, and the support 38, it being welded or otherwise fastened to the latter. For greater rigidity and freedom from possible vibration the rod 40 may be extended into a bearing in an insulating support ring 41, the latter being held in place within the pole piece 42 by welding a ring 43 to the pole piece as shown. It is preferable that the effective length of the rod 40 together with the cathode 33, from a point adjacent the center of the cathode to the free end of the rod, be substantially a quarter wave length long, or an odd multiple thereof, at the mean operating frequency of the magnetron. This will cause a potential mode to exist at the center of the cathode and provide a symmetry of operating potentials conducive to improved operation of the magnetron.

It will be observed that between the two semi-cylindrical members 36 and 37 there are oppositely disposed slots 44 extending the whole length of the members. It has been found that during operation of the magnetron there may be a tendency for free electrons to pass through this slot and energize other structural parts of the magnetron so that the latter tends to oscillate at an undesired mode. It is to be remembered that in a structure such as the one being described wherein the frequency of oscillation is dependent upon the dimensions of the structure it becomes difficult to always force oscillations to occur at the desired mode. To shield other parts of the magnetron from electrons which may tend to pass through the slot 44, a circular shield 45 is fastened to the member 39 as shown in detail on Fig. 2 of the drawing.

The magnetron is evacuated through holes 46 in the central support member 35 and when the vacuum has been drawn the magnetron is sealed off at the tip 47.

As above described the cathode comprises two filamentary windings so mounted and energized as to constitute a bifilar filament. The windings are preferably of thoriated tungsten. In a bifilar filament the current in adjacent turns flows in opposite directions with the result that the magnetic field due to the current is substantially neutralized. If alternating current is employed to energize the cathode, as is usually the case in practice, the small amount of residual alternating flux is insufficient to appreciably modulate the magnetron output current. Power for energizing the cathode may be applied by connecting the power supply leads to the terminals 48 and 49, these terminals being screwed onto threaded rings 50 and 51 respectively. The rings are brazed to the metal cups 26 and 27 thus insuring good electrical connections throughout. If it is desired that a connection be made to the electrical center of the cathode this connection may be made to the ring 52, which is screwed to the threaded ring 53, the latter being welded to the metal cup 28.

In the magnetron of my invention a tuning structure is also provided which is the subject matter of another of my inventions described and claimed in my copending application Serial No. 626,130, entitled "Adjustable magnetron," and filed November 1, 1945.

Many modifications of my invention will occur to one skilled in the art and it is my intention that my invention be not limited to the single embodiment shown but only by the scope of the appended claims:

What is claimed is:

1. Supporting means for a cathode for an electron discharge device comprising a first conoidal body mutilated at the apex to provide an essentially semicircular end and having an annular base end, a second conoidal body arranged coaxially with said first conoidal body and also mutilated at the apex to provide a similar essentially semicircular end and forming with said first mentioned arcuate end a circle, said second conoidal body having an annular base end, and mounting means comprising separate conducting portions and an insulating portion therebetween, said conducting portions each mounting a base end.

2. Supporting means in accordance with claim 1 wherein the annular base end of one conoidal body is smaller than the base end of the other body and wherein the conducting portions of said

mounting means and the insulating portions therebetween form a stepped surface.

3. A cathode comprising a filament, a first conoidal body mutilated at the apex to provide an essentially semicircular end and having an annular base end, a second conoidal body arranged coaxially with said first conoidal body and also mutilated at the apex to provide a similar essentially semicircular end and forming with said first mentioned semicircular end a circle, said second conoidal body having an annular base end, supporting means comprising separate conducting portions and an insulating portion therebetween, said conducting portions each mounting a base end, said conoidal bodies being spaced one from the other, and means connecting said filament to said semicircular ends.

4. A cathode as claimed in claim 3 in which said filament comprises a bifilar filamentary winding.

5. A cathode as claimed in claim 3 in which said filament comprises a bifilar filamentary winding and said means connecting the cathode to the semicircular ends comprises a pair of substantially semi-cylindrical members, each member being connected to one terminal of said winding and to one semicircular end.

6. A cathode as claimed in claim 3 in which said filament comprises a bifilar filamentary winding and which further comprises a center support for said filament, means connecting one end of said center support to the center of said winding, and means arranged on the other end of said support for directly connecting said support to said envelope.

7. A vacuum tube for operation over a predetermined range of frequencies comprising an envelope, a cathode filament inside said envelope, a first conoidal body mutilated at the apex to pro-

vide an essentially semicircular end and having an annular base end, a second conoidal body arranged coaxially with said first conoidal body and also mutilated at the apex to provide a similar essentially semicircular end and forming with said first mentioned semicircular end a circle, said second conoidal body having an annular base end, said supporting means forming part of said envelope and mounting said conoidal bodies inside said envelope and spaced one from the other, means connecting the ends of said filament to said semicircular ends, and a central supporting rod having one end connected to said envelope and the other end connected to the center of said winding, said rod extending beyond said filament connection a distance substantially equal to a quarter wave length of the operating frequency of said tube, whereby said cathode is maintained at substantially radio frequency ground potential.

20 8. A vacuum tube according to claim 7 further comprising shielding means surrounding both said semicircular ends and said means connecting said filament to said ends and a connection between said shielding means and one only of said semicircular ends for confining the emission from said filament.
